UNITED STATES PATENT OFFICE.

THOMAS S. HOLT, OF FEDERALSBURG, MARYLAND.

ACETYLENE-GAS GENERATOR.

No. 833,600.

Specification of Letters Patent.

Patented Oct. 16, 1906.

Application filed February 6, 1905. Serial No. 244,881.

To all whom it may concern:

Be it known that I, THOMAS S. HOLT, a citizen of the United States, and a resident of Federalsburg, in the county of Caroline and State of Maryland, have invented a new and Improved Acetylene-Gas Generator, of which the following is a full, clear, and exact description.

10 The invention relates to an acetylene-gas generator of that class in which a quantity of calcium carbid is discharged into a mass of water, generating the gas, which is subsequently conducted to the gas-holder, the gas-holder being connected with devices by which the carbid-supply is automatically regulated according to the amount of water in the holder.

15 The invention resides in certain novel features involved in the carbid-feed valve and in the mechanism for automatically operating this valve according to the pressure in the gas-holder.

20 The invention also relates to other features of major or minor importance involving the construction and arrangement of various parts of the generator.

25 Reference is had to the accompanying drawings, which represent as an example the preferred embodiment of my invention, in which drawings like characters of reference indicate like parts in the several views, and in which—

30 Figure 1 represents a vertical central section of the complete apparatus, taken through the carbid-chamber and float-chamber. Fig. 1^a is a detail of the closing-arm for the carbid-valve. Fig. 2 is an elevational view with parts broken away to show the gas-delivery chamber. Fig. 3 is a plan view of the complete apparatus. Fig. 4 is a detail section showing the vent-cock, and Fig. 5 is a similar view with the cock in a different position.

is located in the regulator or float-chamber and has connected thereto a rod 32, which extends downward below the regulator-chamber and is pivoted at its lower end to a lever 33. This lever extends horizontally into the generating-chamber 18 and is in turn connected with a rod 34, extending upward through a vertical, elongated division 35 in the generating-chamber to the upper part of said chamber. The upper end of the rod 34 is connected to a lever 36, extending horizontally to a point under the conduit 21, and this lever is joined by a link 37 to an arm 38. The arm 38 extends freely through a slot in the shelf 28 and is hinged to the valve-case 25, as shown, said arm being widened at its upper or hinged portion to form a closure for the discharge-opening of the valve-case and being pivotally connected with the valve-stem 27, as shown.

The water in the tank 10 enters the generating-chamber through the division 35 to the level of the main body of water, and said water also enters the chamber 29; but the level of the water in the chamber is dependent upon the pressure of gas in the same, the level dropping as the pressure rises. This dropping of the water in said chamber will be followed by a dropping of the float 31, and through the various connections 32, 33, 34, 35, 36, 37, and 38 when the float drops the valve 26 will be closed, as indicated in Fig. 1. As the gas is withdrawn from said chamber and the pressure thereby diminished the water rises in the gas-holder, lifting the float 31, and by a reverse action of the said connections 32, 33, 34, 35, 36, 37, and 38 the carbide-valve is opened, delivering a further supply of carbide into the generating-chamber and producing further generation of gas.

The gas generated in the chamber 18 rises in the conduit 21 and is conducted therefrom by means of a pipe 39, passing from the conduit to one port of a three-way valve 40. From another port of said valve a pipe 41 extends to the gas-holder or float-chamber 29. 42 indicates a pipe passing from the pipe 41 to the delivery-regulator, to be described hereinafter.

From the third port of the cock 40 a pipe 47 passes to a vent-pipe 46, leading from the lower part of the chamber 29. The cock 40 is operated by a handle 44, attached to the stem of the cock and connected also to the rod 11 and to a rod 45. The rod 45 is adapted to engage the closure 23 of the chamber 22, and the arrangement is such that when the cock is in the adjustment shown in Fig. 5 the rods 11 and 45 lock the parts 17^a and 23, and when the cock is thrown to the position shown in Fig. 6 the rods 11 and 45 will disengage said parts 17^a and 23 and permit the gate 17 to be opened and the closure 23 to be removed. By these devices upon the proper adjustment of the valve 40 the gas from the

generating-chamber may be conducted directly to the regulator-chamber 29 and at the same time withdrawn by the pipe 42 to the delivery devices and service-line, also by further adjustment of the valve 40 the connection with the regulator chamber and service-line may be cut off and the generating-chamber connected with the vent 46, so as to vent or blow off any gas that may be contained in the generator preparatory to opening the chamber for cleaning or repairing. The parts 17 and 23 cannot be opened until this latter adjustment is made.

As shown best in Fig. 2, the pipe 42 carries the gas to a bell 55, the lower end of which is submerged in the water in the chamber 10. Said bell is free to move vertically and is guided by a rod 56, attached to the bell and sliding in a bracket 57, attached to the walls of the chamber and holder 29. On the discharge end of the pipe 42 is a fitting 58, containing a valve 59, which is pivoted to a weighted lever 60, fulcrumed on the fitting. Said lever is arranged to be engaged by the bell as the same drops, thereby opening the valve 59. As the bell rises the valve is closed by the weighted lever. In this manner the discharge of gas from pipe 42 is regulated. The gas is withdrawn from the top of the bell 55 by a pipe 61, which passes down under the bell and out through the tank 10 into a scrubber 66. (See Fig. 3.) 67 indicates the service-pipe passing from the scrubber-chamber. This chamber contains coke 63 or other substance for filtering or scrubbing the gas. In the upper part of the chamber 62 is arranged a bag 64, of felt or like fabric, distended by a gauze frame, which bag serves further to clean the gas passing through it. The bag is attached to a top section 65 in the chamber 62, and this section has the service-line 67 leading from it and a cover 66, as shown.

From the foregoing description it is thought that the use and operation of my invention will be understood. It will be observed that the parts 17 and 23 cannot be opened until the valve 40 is thrown into venting position, thus avoiding completely any danger of the gas escaping in the vicinity of the generator. The gas passes by the pipe 42 into the bell 55 and its discharge thereinto is automatically regulated, as explained. It then passes through the purifier or scrubber into the service-line, as shown in Fig. 3.

Various changes in the form, proportions, and minor details of my invention may be resorted to at will without departing from the spirit and scope thereof. Hence I consider myself entitled to all such variations as may lie within the terms of my claims.

Having thus described my invention, I claim as new and desire to secure by Letters Patent—

1. In an acetylene-gas generator, the com-

bination with a carbid-chamber and generating-chamber, of a valve-case having a passage therein opening at one end and provided with a lateral communication with the carbid-chamber, a valve sliding in the case, a swinging arm located outside of the case at the discharge end of the said passage therein and having connection with the valve, and means for operating the arm.

10. 2. In an acetylene-gas generator, the combination with a carbid-chamber and generating-chamber, of a valve-case having a passage therein opening at one end and provided with a lateral communication with the carbid-chamber, a valve sliding in the case, a swinging arm located outside of the case at the discharge end of the said passage therein and having connection with the valve, and means for operating the arm, the valve being 15 tapered at one end and having its large end adjacent to the discharge end of the passage in the case.

3. In an acetylene-gas generator, the combination with a carbid-chamber and generating-chamber, of a valve-case having a passage therein opening at one end and provided with a lateral communication with the carbid-chamber, a valve sliding in the case, a swinging arm located outside of the case at 20 the discharge end of the said passage therein and having connection with the valve, and means for operating the arm, the valve being tapered at one end and having its large end adjacent to the discharge end of the passage, 25 and a stem connected to said large end of the valve and forming a connection between the valve and said swinging arm.

4. In an acetylene-gas generator, the combination with the carbid-chamber and generating-chamber, of a valve-case lying horizontally and communicating with the carbid-chamber at its upper side, one end of the valve-case being open, a valve arranged to slide in the valve-case, said valve being tapered and having its larger end adjacent to the open end of the valve-case and being movable back and forth from a point adjacent to said open end of the valve-case to a point beyond the communication with the carbid-chamber, and means for operating the valve, said means for operating the valve comprising a swinging arm mounted in the open end of the valve-case and adapted when the valve is in its innermost position to 45 close said open end of the case.

5. An acetylene-gas generator having a

water-tank, a generator-chamber mounted therein, a carbid-chamber arranged over the generator-chamber, a valve controlling the discharge from the carbid to the generator-chamber, a float-chamber arranged in the water tank and communicating therewith, a float in the float-chamber, a connection between the float and the valve, and means establishing communication between the upper portions of the generator and float-chambers for the purpose specified.

6. An acetylene-gas generator having a water-tank, a generator-chamber arranged therein, a carbid-chamber located over the generator-chamber, a valve communicating the carbid discharge into the generator-chamber, the lower part of the generator-chamber having an opening therein admitting the water from the tank, a division-wall 70 located in the generator-chamber and communicating with said opening, the division-wall forming a passage extending upward in the generator-chamber to a point above the normal water-line therein, said passage being 75 open at its upper end, a float-chamber located in the water-tank and having its lower end open thereto, a float in the float-chamber, connections between the float and valve, said connections including parts passing 80 through the opening in the generator-chamber and upward through the said passage therein, and means establishing communication between the upper portions of the gas-holder and the float-chamber.

7. An acetylene-gas generator having a water-tank, a generating-chamber located therein and having communication with the tank at the lower portion of the generating-chamber, a carbid-chamber mounted over 95 the generating-chamber, a carbid-valve, a float-chamber mounted in the water-tank and open thereto at the lower portion of the float-chamber, a float in the float-chamber, a connection between the float and carbid-valve, and means establishing communication 100 between the upper part of the generating-chamber and the upper part of the float-chamber.

In testimony whereof I have signed my name to this specification in the presence of two subscribing witnesses.

THOMAS S. HOLT.
